[57] **CLAIM**

The ornamental design for a jewelry chain separator, as shown and described.

DESCRIPTION

FIG. 1 is a perspective view of a jewelery chain separator showing my new design;

FIG. 2 is a right side view thereof, the right and left side views being identical;

FIG. 3 is a top view thereof;

FIG. 4 is a bottom view thereof;

FIG. 5 is a front view thereof;

FIG. 6 is a rear view thereof; and,

FIG. 7 is a perspective view of a jewelry chain separator showing my new design, all views not shown are like those of the first embodiment except for the orb ornamentation shown on the top surface.
